UNITED STATES PATENT OFFICE.

HENRY REGENAUER, OF ST. PAUL, MINNESOTA.

KNOCKDOWN BUILDING.

Application filed May 17, 1924. Serial No. 713,946.

To all whom it may concern:

Be it known that I, HENRY REGENAUER, a citizen of Germany, residing at St. Paul, in the county of Ramsey and State of Minnesota, have invented certain new and useful Improvements in Knockdown Buildings, of which the following is a specification.

The present invention relates to buildings, and more particularly to a knock-down building constructed of molded units of cementitious material.

An object of the present invention is to construct a building of cast units of cementitious material.

Another object is to make building units of a cementitious material, which units may be assembled into buildings of different sizes and shapes.

Another object is to make a building by assembling interlocking units of cementitious material.

In order to attain these objects, there is provided, in accordance with one feature of the invention, vertical columns having recesses therein in which wall panels may be inserted, and across the tops of which, interlocking beams are anchored by means of reinforcing rods extending above the tops of the vertical columns and penetrating the interlocking beams. Roof panels are laid transversely on top of longitudinal interlocking beams, and are held in position by a reinforcing unit embedded in each roof panel, a portion of which reinforcing member extends beyond the lower surface of the roof panel to engage a beam. A ridge cap for the roof is composed of overlapping angular members, the end members of which may be ornamented as desired.

These and other features of the invention not specifically mentioned will be more fully brought out in the following description and the accompanying drawings, wherein similar reference characters refer to the same parts throughout the various views.

Referring to the drawings:

Figure 1, is a view in isometric projection of a knock-down building, suitable for use as a garage, made in accordance with the present invention.

Figure 2, is a view in isometric projection of a top interlocking plate for a side wall, an intermediate roof support beam, and a ridge beam, all in the position they would occupy in a completed building, an end panel 14 being indicated in dotted lines.

Figure 3, is a view in isometric projection of a roof panel.

Figure 4, is a view in cross section of a portion of a roof panel showing a positioning member imbedded therein.

Figure 5, is a view in isometric projection of a roof ridge-cap member.

Figure 6, is a view in isometric projection of a T-shaped cross beam.

Figure 7, is a view in isometric projection of a corner column.

Figure 8, is a view in isometric projection of a wall panel having a portion thereof broken away to show a reinforcing metal mesh imbedded therein.

Figure 9, shows a wall panel having a window incorporated therein; and

Figure 10, is a view in isometric projection of a corner of a cement base with a column positioning socket imbedded therein.

Referring to the drawings in detail:

A concrete base 1 is provided with sockets 2 at each point where the center of a column A is to rest. The sockets 2 may be formed by imbedding a portion of metal pipe in the cementitious material of which the base 1 is made while the material is still soft. Each column A has a reinforcing member 4 of metal rod which may extend the entire length thereof and which projects both at the top and at the bottom thereof to form an anchor. Sides of columns which are to hold panel sections are routed as at 5 to engage the ends of panels to be inserted therein. Sides of columns which are to have a door 35 adjacent thereto are rabbeted as at 6, and on a side of an opening which is to support the door, pivot pins 7 are imbedded in the cementitious material of which the column is constructed, while it is in the process of being molded.

Columns in opposite side walls of a structure are interlocking connected in pairs by means of T-beams B which interlocking engage the columns by means of the anchor rods 4 which are inserted in holes 3 in the opposite ends of the horizontal portion of the T-beam. T-beams which are to receive a door 35 are rabbeted as at 8 to permit the door to seat therein. Where it is desired to have but a single door in a unit, the rabbet extends but half way across the T-beam B and a central column 36 is provided as indicated in dotted lines in Figure 6. The T-beam should be reinforced as by a rod 9 encircling each anchor hole at the ends of

the cross member of this beam, and extending upwardly in the form of a loop in the central upright portion thereof. T-beams are routed as at 10 on each side of the central upright portion and on the upper side of the cross member to receive end panels 14 to be later described in detail. Intermediate each laterally adjacent pair of upright columns in the wall portions of a building, panels C are inserted, by sliding from the top downward. It is optional where window panels 26 are placed since these panels are of the same dimensions externally as a solid panel. The panels are of inverted V-shape on top and bottom for the purpose of preventing rain from driving through a joint between vertically adjacent panels.

Resting one upon each end of the T-shaped cross members, are plates 11 which may extend the entire length of a building unless the building is too long to permit handling of a beam of such length. The ends of anchor members 4 extend entirely through and beyond T-members B and the ends of these anchor rods are inserted in holes 12 (see Figure 2) of the plates 11. The plates 11 interlockingly connect the wall units which make up a side of a building.

Resting upon the top of each central upright portion of the T-beam, is a ridge-beam 13 of the shape shown in Figure 2, and this ridge beam has notches 37 in the sides thereof to engage and support end panels 14 inserted therein. The ridge beam 13 is held securely in place, and interlockingly supports T-beams B, by means of anchor rods 15 (see Figure 6), which engage holes 16 in the ridge beam.

Triangular panels 14 slip into position from above and are interlockingly engaged by notches in plates 11, ridge beam 13, and the routings 10 in the sides of the upright portion and the top of the cross portion of the T-beams. Each triangular panel member 14 has a notch 38 located centrally of the upper edge of the panel, said notch having vertical sides and a horizontal bottom. Resting in these notches, and supported therein is a beam 16 which gives an added support to roof slabs carried thereon.

Roof slabs 17 may extend the entire length of the slope of the roof in a small building, such as a garage, and constructed to overlap at the edges as illustrated at 18 in Figure 1. The upper tongue 19 of the overlapping portion has a straight outer side, and the under surface thereof is parallel with the top plane of the slab. In the lower tongue 20 of the overlapping joint, the outer side thereof is straight, but the top surface thereof slopes down inwardly from the edge to form a trough or gutter to carry down rain water. The inward and downward

sloping of this surface also prevents capillary action in this joint, which would be present if the adjacent surfaces of the joint were contiguous throughout. The lower edge 21 of the panels may be scalloped or otherwise patterned as desired. Slabs for either end of a roof section are made with an overlap tongue on but one edge as illustrated, the other edge being finished square. The roof slabs are held in position by friction, and the weight of the material of which they are constructed, but an additional anchoring means is provided in a member 22 imbedded in the slab, the nose portion 23 of which extends beyond the surface of the slab, and may hook over the top edge of the supporting beam 16. A ridge covering is formed of successive slabs 24 of inverted V cross section and having overlapping joints between adjacent sections, of the same general nature as those between adjacent roof slabs. End ridge slabs may be decorated as shown at 25 if desired.

Upon the erection of a building made in accordance with the present invention, all exposed joints may be given a light coat of cement to seal them. This cementing of the joints does not affect the demountable feature of the building, since such a joint will not be of equal strength with the building units which it joins, and the units are easily separable at such joints.

A window panel 26 is constructed of the same exterior shape as an ordinary wall panel. A molded retaining rim 33 forms a frame which extends inwardly from three sides of an opening 27 in the panel, and a bar 28 is suspended from a staple 29 imbedded in the cementitious material during the process of molding. The rod 28 is provided with a slot 31 which fits over a stud 32 imbedded in the body of the slab on the opposite side of the window from the staple 29. A locking pin 30 may be suspended from a chain secured to a staple or other means also imbedded in the body of the slab during the molding thereof. A window 39 is slidably inserted in the frame 33 and may be locked in place by swinging the bar 28 across the top of the window, slipping the slot 31 over the stud 32 and inserting the locking pin 30 in a hole 34 in stud 32.

The building shown in Figure 1 is the only one of various types which may be constructed in accordance with the invention herein disclosed, others being immediately apparent to a mechanic or one skilled in the art. It is, therefore, not intended to limit the invention to the building illustrated, but to include all which come within the spirit and scope of the invention. Buildings made in accordance with the present invention may be set up and disassembled without the use of tools.

other than a trowel, which may be required if it is desired to cover the cracks with a light coat of cement after the building is erected.

6. What I claim is:

1. A knock-down building of the character described having a wall structure consisting of grooved columns spaced apart, anchor bars projecting therefrom, removable wall panels slidably inserted between said columns to be supported thereby, cross beams to interlockingly join opposite wall sections, a longitudinal beam supported by the grooved columns to engage the anchor bars projecting from the columns to interlockingly connect laterally adjacent wall sections, an upright member integral with a cross beam, a ridge beam supported on the upright member to position said upright engaging said ridge beam, and panels supported by the ridge beam and the interlocking beam supported by the columns to form a roof.

2. A knock-down building of the character described, having a wall structure consisting of grooved columns spaced apart, anchoring means integral with said columns, removable wall panels intermediate of and supported by said columns, means for inserting a door between a pair of said columns, means for unitarily interlocking said columns longitudinally of a wall by a member engaging the anchoring means integral with said columns, cross beams interlockingly engaging opposite walls by the anchoring means integral with the columns, upright members carried by the cross beams, a ridge beam connected to the upright member, and panels having non-contiguous rain-proof joints supported on the ridge beam and the walls to form a roof.

3. A knock-down building of the character described, having a wall structure consisting of interlocked panelled units, means for inserting a door in place of a panelled unit in a wall, and a roof structure comprising cross beams interlockingly connect-

ing opposite walls, and roof panels supported by the beams and each having rabbeted side edges of differing angles for overlapping the non-similar rabbeted side edges of the adjacent panels whereby to provide an overlapping, non-contiguous joint between adjacent panels with an enclosed rain passage.

4. A knock-down building of the character described, having a cementitious floor, a wall structure consisting of units interlockingly connected, cross beams interlockingly connecting opposite walls, grooved uprights supported by the cross beams, notched panels supported by the cross beams and the grooved uprights, beams interlockingly seated in the notches of the panels, a ridge beam anchored to the tops of the grooved uprights, roof panels supported by the ridge beam, and the beam seated in the panel notches, means for securing the roof panels to the beam supported in the notched panels, and a ridge covering of molded sections relatively overlapping and having non-contiguous joints therebetween.

5. A knock-down building of the character described having a wall structure consisting of columns spaced apart, removable panels closing the spaces between said columns, a removable beam resting above the panels, anchors for securing the beam to the columns and cross beams extending transversely of the building also engaging said anchors to support a roof.

6. A knock-down building comprising side wall columns, inverted T-shaped cross beams connecting opposing columns, longitudinal side beams seating on the ends of the cross beams for connecting adjacent columns, a common anchor for each column and the superposed portions of the cross and longitudinal beams, and a ridge beam connecting the uprights of the T-shaped cross beams.

In testimony whereof I affix my signature.

HENRY REGENAUER.
